CLAIM

The ornamental design for a pet water fountain as shown and described.

DESCRIPTION

FIG. 1 is a front-top perspective view of a pet water fountain showing our new design;

FIG. 2 is a rear-bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depicting the remainder of the pet water fountain form no part of the claimed design.
